SICKLE DRIVE

Ivor C. Rogers and Leonard M. Krause, Toronto, Ontario, Canada, assignors to Massey-Harris-Ferguson Limited, Toronto, Ontario, Canada, a corporation of Canada

Application January 6, 1955, Serial No. 480,167

3 Claims. (Cl. 74—60)

This invention relates to reciprocating cutter mechanisms for severing a growing crop. It relates, more specifically, to a sickle drive of the wobble type and finds particular utility in agricultural machines such as mowers, harvesters and the like.

It is an object of this invention to provide an improved wobble drive for a reciprocating knife, commonly referred to as a sickle.

It is a more specific object of this invention to provide a whole drive sickle having means for restricting the rotative input motion to one direction, namely, a purely reciprocatory direction of the knift; the twisting moment due to the rotation of the input drive is absorbed by the main frame which supports the drive mechanism.

It is another object of the invention to provide an improved knife drive which eliminates, to a substantial degree, friction and consequent wear on the knife, knife guides, wear plates and holdown clamps and results in a highly efficient knife drive requiring a minimum of adjustment and servicing.

It is still another object of this invention to provide a highly compact knife drive mounted to supporting structure in such a manner so as to localize any vibratory forces which may occur and prevent them from being transmitted to other component parts of the machine.

It is another object of this invention to provide a knife drive unit and its associated knife which are mounted directly and solely on a support means which also supports the coacting guards which results in being able to accurately register the coacting parts of the cutting mechanism, within manufacturing tolerances, and maintain such registry without further adjustment once the initial alignment has been made.

It is still another object of the invention to provide a relatively simple knife drive which is economical to manufacture and efficient in performing the functions for which it is designed.

Other objects and advantages of this invention will become more apparent as this disclosure progresses, reference being had to the accompanying drawing, in which:

Figure 1 is an elevational end view from the inner, or knife, side of the mechanism, with certain parts in section and parts broken away. This view is taken on the line 1—1 of Figure 2.

Figure 2 is an elevational front view of the device shown in Figure 1 partially in section, with certain parts removed for the sake of clarity.

Figure 3 is a plan view, on an enlarged scale, with certain parts of the driving mechanism removed for the sake of clarity.

Figure 4 is an elevational end view, on an enlarged scale, from the outer side of the mechanism, partially in section, and certain parts removed for clarity in the drawings.

Figure 5 is a view of the driving shaft, in the same position it occupies in Figure 2, but on a reduced scale.

Figure 6 is a view of the reciprocating member, in the

2

same position it occupies in Figure 2, but on a reduced scale.

The mechanism to which this invention relates is generally carried by a supporting framework at the forward end of an agricultural machine and at a substantially constant attitude to the ground over which it traverses. This frame may be of any suitable design and in this embodiment is shown in Figure 1 as comprising angle member 10, support member 12, laterally extending plate 14 and a ground engaging shoe 16 all of which are rigidly secured together to form a supporting structure or frame.

Wobble drive means

The support for the drive is in the form of a housing 18 having a pedestal portion 20 which is secured by cap bolts 22 passing through apertures 23 and threadably engaging plate 14, and also by bolts 24 extending through plate 14 and engaging nuts 25. The upper portion of housing 18 has a bore 26 extending therethrough (Figure 2). Counterbores 27 and 28 at either end of bore 26 form seats for the outer races 33a of the roller bearing assemblies 33. These anti-friction bearings take the axial thrust in either direction on the shoulders 31, 32 which are formed by bores 26, 27 and 28. Outwardly extending arms 34, 35 form a rigid bracket support and each have a bore 34a, 35a, respectively (Fig. 4) in their free end in which is mounted anti-friction ball bearing assemblies 37, 38 respectively.

An input drive shaft 40 is rotatably mounted within bore 26 in bearing assemblies 33. An inner end cap 41 is mounted on a reduced portion 42 of shaft 40 and has a driving sprocket 43 rigidly secured thereto. A cap bolt 44 extends through cap 41 and is threadably engaged in a tapped hole 45 in the end of shaft 40, thus securing shaft 40 within housing 18 from axial displacement in one direction. Inner surface 46 of cap 41 bears against the shoulder 40' (Fig. 5) formed between the shaft 40 and reduced portion 42 which prevents bolt 44 from drawing cap 41 too tightly against housing 18 and insures a free running fit between the outer annual flange 48 of cap 41 and housing 18. The outer end of shaft 40 is formed with a shaft portion 50 which is eccentric or offset at an angle to the axis of shaft 40. Annular flange 52, which is formed as an integral part of shaft 40, serves to enclose the outer side of housing 18 in the same manner as does flange 48. The shaft 40 is thus enclosed within housing 18 on anti-friction bearings which are sealed from foreign matter such as dust and dirt. Power is supplied to this mechanism through sprocket 43.

Reciprocating member

A reciprocating member 55 is mounted on shaft portion 50 and comprises a collar portion 57 (Fig. 2) mounted on ball bearing assembly 59 carried on shaft portion 50, and a downwardly extending arm portion 60 formed integral with collar 57. Bearing assembly 59 is retained on a reduced portion 61 of shaft 50 by means of a washer 62 and nut 63 threadably engaged on shaft 50. An outer cover 64 is secured by bolt and nut means 65 to collar 57 and has an annular flange 67 which bears against, and prevents axial displacement of, the bearing assembly 59.

Intermediate member

Downwardly extending arm 60 is connected to the reciprocating knife 70 by an intermediary which takes the form of a swinging yoke 72. The upper end of the arms 74, 75 of yoke 72 are pivotally connected to the bracket arms 34, 35 respectively, of the drive housing by means of pins 77, 78 journaled in bearing assemblies 37, 38.

The upper ends of arms 74, 75 are spaced apart sufficiently so as to resist any twisting moment in a plane containing it and to insure that the yoke 72 is capable of only oscillatory movement in the direction of knife travel as shown by the curvilinear arrows in Fig. 2.

The lower bight portion 80 of yoke 72 has a recess 82 (Fig. 4) into which is inserted the ball bearing assembly 84. Assembly 84 receives the lower free end of arm 60 and as the latter is drivingly oscillated, the yoke 72 oscillates therewith.

Cutting mechanism

A lug 86 having an aperture 86a (Fig. 4) therethrough extends downwardly from yoke 72 and is secured to the knife connector, or clevis, 88 by nut and bolt means 89 extending therethrough. Clevis 88 is secured to the leaf spring 69 and cutter bar 70 of the knife assembly by rivets 87.

The cutter bar 70 has secured along its length the conventional knife sections 71 by means of rivets 74a. Conventional knife guides 76 are secured along the length at spaced locations, of plate 14 and extend over the knife as shown in Figure 1. A wear plate 76' is secured along the length of the forward edge of plate 14 and absorbs the rearward thrust of the knife assembly through cutter bar 70. Knife guards 78 having ledger plates 78' secured therein, are also secured along the length of plate 14 by means of the bolts 79 (Fig. 3). A hold down clamp 81 is secured by cap bolts 83 to the horizontally disposed plate 85 which in turn is rigidly mounted on plate 14 by bolts 24 and nuts 25. The rearward end 81' of clamp 81 bears against the top surface of the end knife section 72' and acts to hold it down in sliding engagement therewith. It is important that the knife sections 71 register properly with the guards 78 for proper cutting and to maintain such registry has been a troublesome matter in the past. With the present invention, however, both the knife sections 71 and the guards 78 are accurately located with respect to each other because of the fact that the mounting, or pedestal, 20 and the guards 78 are both secured to a common plate 14. Therefore, the spacing of the holes in which guards 78 and pedestal 20 are secured can be held within close manufacturing tolerances and registry of these parts assured. In other words the pivotal point 85 is fixedly located with respect to the knife guards 78. Furthermore, point 85 is located very closely to the knife in a vertical direction and therefore the moment arm or driving couple is minimized; furthermore, arcuate movement of point 89 is negligible. It will be noted that the entire drive unit is located in the same vertical plane as the driven knife.

By so mounting this compact drive unit any knife unbalance is confined to the cutter bar and drive itself and is not transmitted to other intermediate support members.

Operation

In operation, power is supplied through a flexible belt such as a chain (not shown) to sprocket 43 which causes shaft 40 and its eccentric portion 50 to rotate therewith.

The wobble motion of eccentric shaft 50 is translated into a swinging motion of the arm 60 and in addition there is a considerable rotative force on arm 60 tending to make it rotate in the direction in which the shaft 40 is driven. If the lower end of reciprocating member 60 was connected directly to the knife head, this tendency

to rotate would cause considerable friction and wear between the wear plate 76' and cutter bar 70, knife sections 71, guides 76, guards 78 and ledger plates 78'. These frictional forces are of considerable magnitude in high-speed cutters of this type and cause this type of mechanism to require frequent adjustment, alignment and servicing. However, by the use of an intermediate member, such as the yoke 72, the rotative force or twisting moment on the knife due to the rotating input shaft 10 40 is absorbed in the drive housing 18. The rotative force from the input shaft 40 is transmitted through the reciprocating member 60 to the yoke 72 and back to the arms 34, 35 of the housing 18. Only a truly reciprocatory motion in the direction of intended travel is imparted to 15 the knife. After the initial alignment of the knife and its associated parts is made and the knife sections brought into proper registry with the guards, little attention or servicing is required thereafter.

What we claim and desire to secure by Letters Patent 20 is:

1. A drive mechanism for a reciprocating type cutter comprising; a support frame, a housing rigidly mounted on said frame and having spaced bracket arms extending in one direction, wobble means rotatably mounted in said housing, means to drive said wobble means, a member rotatably mounted on said wobble means and having a downwardly extending arm, a yoke member having spaced arms pivotally secured to said bracket arms and having a downwardly extending portion operatively connected with said downwardly extending arm for oscillation therewith, said portion adapted to be pivotally connected with said cutter.
2. A drive mechanism for a reciprocating type cutter comprising; a support frame, a housing rigidly mounted on said frame and having spaced bracket arms extending in one direction, wobble means rotatably mounted in said housing, means to drive said wobble means, a member having a collar portion rotatably mounted on said wobble means and having a downwardly extending arm, 35 a yoke member having spaced arms pivotally secured to said bracket arms and having a downwardly extending portion operatively connected with said downwardly extending arm for oscillation therewith, said portion adapted to be pivotally connected with said cutter.
3. A drive mechanism for a reciprocating type cutter comprising; a support frame, a housing having a bore extending therethrough and also having spaced bracket arms extending in one direction, said housing secured to said frame, wobble means comprising a shaft rotatably mounted in said bore and having an eccentric part, means to drive said wobble means, a member having a collar portion rotatably mounted on said eccentric part and having a downwardly extending arm, a yoke member having spaced arms pivotally secured to said bracket arms and having a downwardly extending portion operatively connected with said downwardly extending arm for oscillation therewith, said portion adapted to be pivotally connected with said cutter.
